ABSTRACT

An induction cooking appliance comprises a bottom metal tray containing a printed circuit board and electronic components mounted thereon, and also a pair of polymeric support elements configured to be fastened to the metal tray and interposed between the tray and the printed circuit board in order to define a predetermined distance between the tray and the printed circuit board. The polymeric support elements may have an integral intermediate polymeric frame which provides a predetermined relative position thereof.

INDUCTION COOKING APPLIANCE AND METHOD FOR ITS ASSEMBLY

CROSS-REFERENCE TO RELATED APPLICATIONS

This application claims priority to U.S. patent application Ser. No. 15/085,529, filed on Mar. 30, 2016, entitled "INDUCTION COOKING APPLIANCE AND METHOD FOR ITS ASSEMBLY," now issued as U.S. Pat. No. 10,349,469, and to European Application EP 15161797.4, filed on Mar. 30, 2015, entitled "INDUCTION COOKING APPLIANCE AND METHOD FOR ITS ASSEMBLING," the disclosures of which are hereby incorporated herein by reference in their entirety.

TECHNICAL FIELD

The present disclosure relates to induction cooking appliances comprising a bottom metal tray containing a printed circuit board and electronic components mounted thereon.

BACKGROUND OF THE DISCLOSURE

According to the disclosure, a way of quickly mounting the printed circuit board on the metal tray without insulation problems is provided. Moreover the technical solution according to the disclosure has a low cost, simple to assemble and easy for packaging.

BRIEF DESCRIPTION OF THE DRAWINGS

Further advantages and features according to the present disclosure will become clear from the following detailed description provided as a non-limiting example, with reference to the attached drawings in which:

FIG. 1 is a perspective exploded view of an induction cooking hob according to the disclosure;

FIG. 2 is an enlarged exploded view of the appliance of FIG. 1 according to a first embodiment of the disclosure, where some components have been omitted for sake of clarity;

FIG. 3 is a perspective enlarged view of a component of FIG. 2;

FIG. 4 is a cross-section of a portion of the appliance of FIG. 2, in an assembled configuration;

FIG. 5 is an enlarged exploded view of the appliance of FIG. 1 according to a second embodiment of the disclosure, where some components have been omitted for sake of clarity;

FIG. 6 is a perspective enlarged view of a component of FIG. 5;

FIG. 7 is a cross-section of a portion of the appliance of FIG. 5, in an assembled configuration;

FIG. 8 is a perspective enlarged view of an elastic fastening component of the coil support according to the disclosure;

FIG. 9 is similar to FIG. 8 where such fastening component is shown in an disassembled configuration;

FIG. 10 is a cross-section view of a portion of the cooking hob of FIG. 1 which shows the fastening component of FIGS. 8 and 9 in an assembled configuration of the cooking hob; and

FIG. 11 is a perspective view of a different embodiment of the component shown in FIG. 3.

related to a display mirror. Accordingly, the apparatus components and method steps have been represented, where appropriate, by conventional symbols in the drawings, showing only those specific details that are pertinent to understanding the embodiments of the present disclosure so as not to obscure the disclosure with details that will be readily apparent to those of ordinary skill in the art having the benefit of the description herein. Further, like numerals in the description and drawings represent like elements.

10 For purposes of description herein, the terms "upper," "lower," "right," "left," "rear," "front," "vertical," "horizontal," and derivatives thereof shall relate to the disclosure as oriented in FIG. 1. Unless stated otherwise, the term "front" shall refer to the surface of the element closer to an intended viewer of the display mirror, and the term "rear" shall refer to the surface of the element further from the intended viewer of the display mirror. However, it is to be understood that the disclosure may assume various alternative orientations, except where expressly specified to the contrary. It is 15 also to be understood that the specific devices and processes illustrated in the attached drawings, and described in the following specification are simply exemplary embodiments of the inventive concepts defined in the appended claims. Hence, specific dimensions and other physical characteristics 20 relating to the embodiments disclosed herein are not to be considered as limiting, unless the claims expressly state otherwise.

The terms "including," "comprises," "comprising," or any other variation thereof, are intended to cover a non-exclusive 25 inclusion, such that a process, method, article, or apparatus that comprises a list of elements does not include only those elements but may include other elements not expressly listed or inherent to such process, method, article, or apparatus. An element proceeded by "comprises a . . ." does not, without 30 more constraints, preclude the existence of additional identical elements in the process, method, article, or apparatus that comprises the element.

With reference to the drawings, an induction cooking hob 10 according to the disclosure comprises a metal tray or box 40 12, a main printed circuit board or PCB 14, induction coil trays 16 and 18 and a top glass plate 20. A plurality of electronic components 22 are mounted. Moreover, on the PCB 14 a heat sink 24 is mounted, which is cooled by a fan 26 mounted on the metal tray 12 adjacent an aperture 12a 45 thereof. The heat sink 24, used to cool down some of the electronic components 22 which generate more heat, can be mounted on a polymeric support element together with the fan 26 and with the electronic components 22. The polymeric support element is contained in the metal tray 12.

With reference to FIG. 2, two support elements 28 made of polymeric material are mounted on the metal tray 12. Each support element 28 is an elongated profile and has an L-shaped cross-section defining a first wing 28a configured to contact the top surface of the metal tray in an assembled 50 position thereof, and a second wing 28b which is vertical in the assembled configuration. As shown in FIGS. 3 and 4, the first wing 28a of each support element 28 is provided with a plurality of ribs 30 while the second wing 28b is provided with a plurality of shaped teeth adapted to cooperate with the PCB 14 after a snap-engagement thereof on the ribs 30, as 55 shown in FIG. 4. Each of the support elements 28 is provided, at distal ends thereof, with an elastic hook portion 34 designed to cooperate, in a snap-engaging assembling movement, with corresponding slots in the metal tray. In this 60 way, the two support elements 28 can be easily and rapidly mounted in the metal tray 12, without any use of tools or the like, so that such elements 28 assume the configuration 65

DESCRIPTION OF THE EMBODIMENTS

The present illustrated embodiments reside primarily in combinations of method steps and apparatus components

shown in FIG. 2. After that, the next assembly step is to snap-engage parallel edges 14a of the PCB 14 on the support elements 28 so that the rear surface of the PCB 14 abuts the ribs 30 of the first wings 28a while the upper surface of the PCB 14 is retained by the elastic hook portions 34 of the second wings 28b. The dimension of the ribs 30 defines, together with the thickness of the first wing 28a, a predetermined distance D of the PCB 14 from the metal tray 12.

In FIG. 11, a different embodiment of the support elements 28 is shown. The support elements 28 are integral with an intermediate flat frame 46 with a grating structure and with portions 46a for fixing such frame 46 to the metal tray, for instance with screws, rivets or the like. In such embodiment, the ribs 30 are integral with the web portions 46b of the frame 46. The use of the intermediate flat frame 46 may be beneficial in reducing possible deformation of the PCB 14 and possible stresses in the welding.

With reference now to FIG. 8, the assembly of the coil trays 16 and 18 on the elastic clips 36 is illustrated. The elastic clips 36 are located in plastic standoffs 38 with central pins 38a snap-engaged in corresponding slots 50 (FIG. 10) of the metal tray 12. The shape of each plastic standoff 38 provides for a proper orientation of the elastic clip 36 itself. The central pin 38b whose cross-section matches the shape of a central bore 36a in the clip 36 can freely slide in a corresponding opening of the coil trays 16 and 18 to provide the proper orientation. The clip 36 generally defines a spring and has two elastic shaped arms A and B, a first curved arm A designed to exert a main elastic force on the coil tray 16 or 18 (configuration shown in dotted lines in FIG. 10), and a second smaller arm B exerting a reduced force on a peripheral zone of the coil tray 16 or 18. In this way, there is a smaller deflection of the coil tray 16 or 18 since the major force exerted by the clip 36 is displaced towards the center of the coil tray 16 or 18.

As described above, the mounting of the PCB 14 on the support elements 28 and the mounting of the coil trays on the elastic clips 36 and on the central pins 38a do not require any special tools and can be carried out easily and quickly.

The assembly of the coil trays 16 and 18 as shown in the above example includes the use of elastic clips 36. However, the trays 16 and 18 can also be supported directly by the metal tray 12 without the interposition of any elastic clips 36. In this case the correct positioning of such tray is provided by bent portions of the bottom of the metal tray 12 which are tongue shaped and substantially orthogonal with the plane defined by the metal tray 12.

With reference to FIGS. 5-7, a second embodiment of the disclosure is shown which is different from the previous one in the shape of support elements 40. While the fastening of each support element 40 to the metal tray 12 is substantially identical to the previous one, i.e. with elastic hook portions 34c provided on distal ends, each support element 40 has a C-shaped cross-section with a first part 40a configured to contact the upper surface of the metal tray 12, a second vertical part 40b (in the installed configuration) and a third horizontal part 40b. As shown in FIGS. 6 and 7, a plurality of ribs 42 are placed on the first and second part 40a and 40b. The plurality of ribs 42 (integral with such parts) present an upper surface 42b at a predetermined distance from the third part 40c of the support element 40, such distance corresponding to the thickness of the PCB 14 inserted between such ribs 42 and the third part 40c of the support element 40. The vertical dimension of the ribs 42 assure (as in the first embodiment) a sufficient distance of the PCB 14 from the metal tray 12 in order to have a proper electrical insulation, with no accidental contacts. For install-

ing the PCB 14 in the support elements 40 it is sufficient to slightly flex the PCB 14 and to insert two parallel edges thereof in the slots defined by the ribs 42 and by the upper third part 40c of each support elements 40. The mounting of the support elements 40 and of the coil trays 16 and 18 is substantially identical to what already described in connection with the first embodiment. Also in this embodiment the support elements 40 can be integral with an intermediate frame 46 as shown in FIG. 11.

The material of the polymeric support elements 28 and 40 can be chosen in a wide range of thermoplastic or thermosetting materials. In order to have a sufficient rigidity of such supports, it is desirable to use a polymeric material (polypropylene, polyamide etc.) with a fiber reinforce (for instance glass fibers).

Moreover, the two different kind of support elements 28 and 40 may be combined together in the same cooking hob, particularly in view of making easier the mounting of the PCB 14 on such supports; in this case one edge of the PCB 14 may be installed in the slot of the support element 40 and the other opposite edge is lowered on the opposite support element 28 and snap-engaged on the elastic hook portions 34c.

Even though in the above examples a single large printed circuit board 14 is shown, a plurality of smaller printed circuit board can also be used, each of them having two support elements 28 snap-engaged with the metal tray 12.

It is clear from the above that each embodiment of the disclosure has the advantage of a very quick and easy mounting of relevant components (printed circuit board and coil trays) onto the metal tray which encompasses all such components, without any need of special tool. Such way of assembling the induction cooking hob can be easily automated and offers a high degree of reliability in assembling operation, which increases the quality of the appliance.

It is well known in the art of induction cooking appliances, particularly of cooking hobs, that essential components are a housing containing the electronic components and a cooling fan, on which supporting plates for induction coils are mounted and on which a glass plate, on which cooking utensil are to be placed, is mounted too. The ways in which such different components can be assembled one with the other can vary quite widely, but the most common technology is to fasten the glass plate to the bottom metal tray after mounting the printed circuit board therein and placing the induction coils on supporting plates which are supported by the tray, with the interposition of elastic elements which urge the induction coils against the glass plate.

Even if for the bottom tray plastic have been used as construction material, the use of metal tray has certain technical advantages, either in terms of low cost or shielding effect from electromagnetic radiations emerging from the power electronic components. On the other hand, the use of a metal tray or plate may present the problem of installation of electrical insulation.

It is an object of the present disclosure to provide an induction cooking appliance with solves the above problem in a simple and economical way. Such object is reached thanks to the features listed in the appended claims.

It will be appreciated that embodiments of the disclosure described herein may be comprised of one or more conventional processors and unique stored program instructions that control one or more processors to implement, in conjunction with certain non-processor circuits, some, most, or all of the functions of an induction cooking hob 10, as described herein. The non-processor circuits may include,

but are not limited to signal drivers, clock circuits, power source circuits, and/or user input devices. As such, these functions may be interpreted as steps of a method used in using or constructing a classification system. Alternatively, some or all functions could be implemented by a state machine that has no stored program instructions, or in one or more application specific integrated circuits (ASICs), in which each function or some combinations of certain of the functions are implemented as custom logic. Of course, a combination of the two approaches could be used. Thus, the methods and means for these functions have been described herein. Further, it is expected that one of ordinary skill, notwithstanding possibly significant effort and many design choices motivated by, for example, available time, current technology, and economic considerations, when guided by the concepts and principles disclosed herein will be readily capable of generating such software instructions and programs and ICs with minimal experimentation.

It will be understood by one having ordinary skill in the art that construction of the described disclosure and other components is not limited to any specific material. Other exemplary embodiments of the disclosure disclosed herein may be formed from a wide variety of materials, unless described otherwise herein.

For purposes of this disclosure, the term "coupled" (in all of its forms, couple, coupling, coupled, etc.) generally means the joining of two components (electrical or mechanical) directly or indirectly to one another. Such joining may be stationary in nature or movable in nature. Such joining may be achieved with the two components (electrical or mechanical) and any additional intermediate members being integrally formed as a single unitary body with one another or with the two components. Such joining may be permanent in nature or may be removable or releasable in nature unless otherwise stated.

It is also important to note that the construction and arrangement of the elements of the disclosure as shown in the exemplary embodiments is illustrative only. Although only a few embodiments of the present innovations have been described in detail in this disclosure, those skilled in the art who review this disclosure will readily appreciate that many modifications are possible (e.g., variations in sizes, dimensions, structures, shapes and proportions of the various elements, values of parameters, mounting arrangements, use of materials, colors, orientations, etc.) without materially departing from the novel teachings and advantages of the subject matter recited. For example, elements shown as integrally formed may be constructed of multiple parts or elements shown as multiple parts may be integrally formed, the operation of the interfaces may be reversed or otherwise varied, the length or width of the structures and/or members or connector or other elements of the system may be varied, the nature or number of adjustment positions provided between the elements may be varied. It should be noted that the elements and/or assemblies of the system may be constructed from any of a wide variety of materials that provide sufficient strength or durability, in any of a wide variety of colors, textures, and combinations. Accordingly, all such modifications are intended to be included within the scope of the present innovations. Other substitutions, modifications, changes, and omissions may be made in the design, operating conditions, and arrangement of the desired and other exemplary embodiments without departing from the spirit of the present innovations.

It will be understood that any described processes or steps within described processes may be combined with other disclosed processes or steps to form structures within the

scope of the present disclosure. The exemplary structures and processes disclosed herein are for illustrative purposes and are not to be construed as limiting.

It is also to be understood that variations and modifications can be made on the aforementioned structures and methods without departing from the concepts of the present disclosure, and further it is to be understood that such concepts are intended to be covered by the following claims unless these claims by their language expressly state otherwise.

What is claimed is:

1. An induction cooking appliance comprising:
a base tray defining a recess and having a lower surface positioned within the recess, the lower surface defining a plurality of apertures;
a printed circuit board spaced apart from and parallel with the lower surface of the base tray; and
a pair of support elements, each of the pair of support elements including:
a horizontal portion integrally formed with a vertical portion;
a hook portion configured to be received by one of the plurality of apertures;
a plurality of ribs extending from the horizontal portion along the vertical portion, wherein each plurality of ribs are disposed in a linear arrangement along a length of a respective support element; and
a plurality of snap-engaging elements positioned on the vertical portion and parallel with the plurality of ribs, the plurality of snap-engaging elements being vertically and horizontally offset from the plurality of ribs, wherein an edge of the printed circuit board is positioned between the plurality of snap-engaging elements and the plurality of ribs.

35 2. The induction cooking appliance of claim 1, wherein the pair of support elements are integrally formed with a frame, the frame shaped to complement the printed circuit board.

3. The induction cooking appliance of claim 2, wherein the frame includes a plurality of webs extending across the frame in a first direction, and further wherein the plurality of ribs extend across the frame in a second direction, the second direction perpendicular to the first direction.

40 4. The induction cooking appliance of claim 1, further comprising:
a plurality of coil supports coupled with the base tray, each coil support including a seat, a central pin, and an elastic arm; and
a coil tray configured to be supported by the plurality of coil supports.

5. The induction cooking appliance of claim 4, wherein the base tray includes an upper surface defining a plurality of slots, and further wherein the seat of each coil support is received by at least one of the plurality of slots such that each coil support is positioned at least partially above the printed circuit board.

6. The induction cooking appliance of claim 4, wherein the elastic arm is positioned between the seat of the respective coil support and the coil tray, the elastic arm configured to bias the coil tray against a glass plate.

65 7. An induction cooking appliance comprising:
a base tray defining a recess and having a lower surface within the recess, the lower surface defining a plurality of apertures;
a printed circuit board positioned within the recess; and
a pair of support elements, each of the pair of support elements including:

- first and second horizontal portions spaced apart by a vertical portion, the first and second horizontal portions being vertically aligned; 5
- a hook portion extending from a distal end of the first horizontal portion and configured to be received by one of the plurality of apertures; and
- a plurality of ribs extending from the first horizontal portion along the vertical portion and disposed in a space between the first and second horizontal portions, wherein an end of the plurality of ribs is spaced apart from the second horizontal portion to define a slot, the slot configured to receive an edge of the printed circuit board. 10
8. The induction cooking appliance of claim 7, further comprising: 15
- a frame integrally formed with the pair of support elements, wherein the frame includes a plurality of webs extending across the frame in a first direction, and further wherein the plurality of ribs extend across the frame in a second direction, the second direction perpendicular to the first direction. 20
9. The induction cooking appliance of claim 7, further comprising: 25
- a plurality of coil supports coupled with the base tray, each coil support including a seat, a central pin, and an elastic arm; and
- a coil tray configured to be supported by the plurality of coil supports, wherein the elastic arm of each coil support is positioned to bias the coil tray upward. 30
10. The induction cooking appliance of claim 9, wherein the base tray defines a plurality of slots, and further wherein the seat of each coil support includes seat hook portions configured to engage with one of the plurality of slots. 35
11. The induction cooking appliance of claim 7, wherein the plurality of ribs of each of the pair of support elements are arranged in a linear configuration along the respective first horizontal portion. 40
12. The induction cooking appliance of claim 7, wherein the hook portion of each support element is a single-armed hook portion including a foot extending outward from the distal end of the respective support element. 45
13. An induction cooking appliance comprising: 45
- a base tray having a lower surface; 50
- a printed circuit board spaced apart from and parallel with the lower surface of the base tray; 50
- first and second support elements, each of the first and second support elements including a horizontal portion and a vertical portion, wherein the first and second support elements are mounted on opposing ends of the lower surface; and
- first and second pluralities of ribs integrally formed with each of the first and second support elements, respec-

tively, each plurality of ribs disposed in a linear arrangement along a length of the respective support element and extending from the horizontal portion along the vertical portion of the respective support element, each of the plurality of ribs having a horizontal upper surface at least partially defining a slot, wherein a first edge of the printed circuit board is positioned on the horizontal upper surfaces within the slot of the first support element and a second edge of the printed circuit board is positioned on the horizontal upper surfaces within the slot of the second support element.

14. The induction cooking appliance of claim 13, wherein at least one of the first and second support elements includes a plurality of engagement features positioned on the vertical portion and parallel with the respective plurality of ribs, and further wherein the plurality of engagement features and the respective plurality of ribs define the slot. 15

15. The induction cooking appliance of claim 14, wherein the horizontal portion and the vertical portion define an L-shaped cross-section across most of the respective support element. 20

16. The induction cooking appliance of claim 13, wherein at least one of the first and second support elements includes a top portion extending parallel to the horizontal portion and further wherein an end of each of the respective plurality of ribs is spaced apart from the top portion to define the slot. 25

17. The induction cooking appliance of claim 16, wherein the horizontal portion, vertical portion, and top portion define a C-shaped cross-section across most of the respective support element. 30

18. The induction cooking appliance of claim 13, further comprising: 35

a frame integrally formed with the first and second support elements.

19. The induction cooking appliance of claim 13, further comprising: 40

a plurality of coil supports coupled with an upper surface of the base tray, each coil support including a seat and a clip, wherein the clip includes a central pin and at least one elastic arm, and further wherein the seat defines a bore shaped to receive the central pin; and a coil tray configured to be supported by the plurality of coil supports, wherein the at least one elastic arm of each coil support is positioned to bias the coil tray against a glass plate. 45

20. The induction cooking appliance of claim 19, wherein the at least one elastic arm includes a first arm and a second arm, the first arm having a first shape and exerting a first force on the coil tray and the second arm having a second shape and exerting a second force on the coil tray. 50
